UNITED STATES PATENT OFFICE.

CHARLES F. HAEBERLE AND FREDERICK F. HAEBERLE, OF PHILADELPHIA,
PENNSYLVANIA.

DESIGN FOR A FINGER-RING.

SPECIFICATION forming part of Design No. 32,353, dated March 20, 1900.
Application filed December 20, 1899. Serial No. 741,067. Term of patent 3 $\frac{1}{2}$ years.

To all whom it may concern:

Be it known that we, CHARLES F. HAEBERLE and FREDERICK F. HAEBERLE, citizens of the United States, residing at Philadelphia, 5 county of Philadelphia, and State of Pennsylvania, have invented and produced a new and original Design for Finger-Rings, of which the following is a specification, reference being had to the accompanying drawings, forming 10 a part thereof.

Figure 1 is a top plan view of a finger-ring, showing our design; and Fig. 2 is a vertical section of Fig. 1.

As shown in the drawings, the leading or 15 material feature of our design consists of a ring the band A of which is formed to represent a horseshoe-nail, the head thereof terminating in a miniature horseshoe B, having a cross-bar C.

One of the main features of the design is 20 that the pointed end of the representation of the horseshoe-nail lies within the horseshoe, thus giving a unique and attractive effect to the general appearance of the ring.

Having thus fully described our invention, 25 what we claim as new is—

The design for a finger-ring, as herein shown and described.

In testimony whereof we have hereunto affixed our signatures in the presence of two 30 subscribing witnesses.

CHARLES F. HAEBERLE.
FREDERICK F. HAEBERLE.
